METHOD OF MAKING ALLOYS OF BERYLLIUM
WITH PLUTONIUM AND THE LIKE

Oliver J. C. Runnalls, Deep River, Ontario, Canada, assignor, by mesne assignments, to the United States of America as represented by the United States Atomic Energy Commission

No Drawing. Application January 7, 1955
Serial No. 480,591

4 Claims. (Cl. 75—122.7)

This invention relates to the production of alloys of beryllium with one or more of the metals uranium, plutonium, actinium, americium, curium, thorium and cerium.

In accordance with the method of the invention a halide salt of the metal to be alloyed with the beryllium is heated in the presence of beryllium, to reduce the halide to metal and cause the latter to alloy directly with the beryllium. Although the heavy metal halides are more stable, thermodynamically, than the beryllium halides, the reducing reaction proceeds to completion if the beryllium halide product is continuously removed by vacuum distillation. The resulting alloy is, therefore, free of fluoride slag.

The pressure during the reaction is preferably maintained at about 10^{-5} mm. Hg, although other vacuum conditions may be employed. The mass is heated to a temperature of 1000° C. to 1350° C. to insure reduction of the halide of the alloying metal. In each case sufficient beryllium is used to complete the reduction and yet leave the desired amount of beryllium to be alloyed with the reduced halide metal.

The following examples are illustrative of the operation:

1. Preparation of plutonium-beryllium alloys

142 mg. of powdered plutonium fluoride PuF_3 was mixed with 64 mg. of beryllium metal powder, and was placed in a beryllium oxide crucible. The charge was heated in vacuum at 1150° C. for 1 hour to reduce the plutonium fluoride with the beryllium to distill the beryllium fluoride BeF_2 formed, and to alloy the plutonium with the beryllium. Since this alloy did not fuse below 1500° C., it was hard sintered by raising the temperature to 1350° C. for fifteen minutes. The resulting alloy was crystalline, weighing 154 mg. and containing 70% plutonium. The plutonium yield in the reduction, therefore, was 94%.

2. Preparation of uranium-beryllium alloys

56.5 mg. of powdered uranium fluoride UF_4 was mixed with 24.2 mg. of beryllium metal powder and placed in a beryllium oxide crucible. The charge was heated in vacuum at 1200° C. for 45 minutes to reduce the uranium fluoride with beryllium, to distill the beryllium fluoride BeF_2 formed and to alloy the uranium with the beryllium.

2

The resulting alloy was crystalline, weighing 59.7 mg. and containing 69% uranium. The uranium yield in the reduction, therefore was 96%.

3. Preparation of actinium-beryllium alloys

15 mc. (200 $\mu\text{g.}$) of Ac^{227} as AcCl_3 was evaporated to dryness on oxalic acid along with 50 mg. of uranium as a carrier. The actinium-uranium mixture was calcined to oxide at 600° C. and fluorinated for 2 hours at 600° C. with a mixture of anhydrous hydrogen fluoride and hydrogen. The resulting fluoride was mixed with beryllium powder to produce a Be to $\text{Ac} + \text{U}$ ratio of about 200 to 1 in the final alloy. The mixture was heated at 5×10^{-5} mm. mercury pressure in a beryllium oxide crucible for 15 minutes at 1350° C. to permit the following reaction to go to completion.

The resulting alloy had melted and formed a small sphere in the bottom of the crucible. During the heat treatment about 50% of the Ra^{223} distilled from the crucible but returned to the alloy with a half-life of 11.2 days.

Alloys thus prepared of beryllium with plutonium, actinium, americium and/or curium are useful as neutron source materials. As these metals are normally available in small quantities and are relatively difficult to handle this method is particularly well adapted to providing such alloys.

It will be apparent that more than one of the alloying metals may be incorporated in the beryllium to produce, for example, an alloy of beryllium, uranium and thorium.

The fluoride of the alloying metal is the preferred halide.

What is claimed is:

1. A method of producing alloys of beryllium with plutonium which comprises mixing halide of plutonium with beryllium and heating the mass at 1000° C. to 1350° C. in vacuum to reduce the halide and alloy the reduced metal with beryllium.
2. The method defined in claim 1 wherein the beryllium halide formed is volatilized from the reaction zone.
3. The method defined in claim 1 wherein the halide is fluoride.
4. A method of producing a plutonium-beryllium alloy which comprises mixing plutonium fluoride with beryllium metal, heating the mass in vacuum at about 1150° C. to reduce the fluoride and alloy the metals and removing the volatile beryllium fluoride formed.
